UNITED STATES PATENT OFFICE.

CHARLES W. NEISWENDER, OF BUCYRUS, KANSAS.

SMOKING PIPE.

Application filed February 19, 1923. Serial No. 620,018.

To all whom it may concern:

Be it known that I, CHARLES W. NEISWENDER, a citizen of the United States, residing at Bucyrus, in the county of Miami and State of Kansas, have invented certain new and useful Improvements in a Smoking Pipe, of which the following is a specification.

The present invention relates to a smoking pipe and has for its principal object to provide a device of this nature constructed with a long passage for the smoke to travel through from the bowl to the mouth stem, said passage being disposed within a pipe stem of the ordinary length.

Another important object of the invention is to provide a pipe of this nature having a stem with a coil passage therein.

Another object of the invention is to provide a pipe of this nature having a stem which may be readily assembled and disassembled for cleaning and repair purposes.

A still further object of the invention is to provide a pipe of this nature which is simple and efficient in construction, reliable, comparatively inexpensive to manufacture, and well adapted to the purpose for which it is designed.

With the above and numerous other objects in view as will appear as the description progresses, the invention resides in certain novel features of construction, and in the combination and arrangement of parts as will be hereinafter more fully described and claimed.

For the purpose of illustrating my invention, I have shown in the accompanying drawing that form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

In the drawing—

Figure 1 is a longitudinal section through the smoking pipe embodying my invention, Figure 2 is a fragmentary elevation of the passage forming device, the end thereof being shown in section,

Figure 3 is a detail perspective of the inner tube, Figure 4 is a detail perspective of the mouth piece, and

Figure 5 is a transverse section taken substantially on the line 5—5 of Figure 1 looking in the direction of the arrow, said view being taken on an enlarged scale.

Referring to the drawing in detail it will be seen that the pipe consists of the usual bowl 1 having the concave bottom 2. A stem 3 is suitably attached to the bowl 1 and communicates therewith through a small opening 4 in the side of the bottom 2. In the bore of the stem 3 there is disposed a passage forming device 5 which is in the form of an elongated bar having a spiral grooved periphery. This bar extends throughout the bore of the stem into a mouth piece 6 suitably mounted on the stem. A tube 7 may be used with the passage forming device 5 if desired and is preferable especially when the device 5 is constructed of wood. This tube is constructed with a conical shaped entrance 8 so as to provide a restricted opening 9 and a space or pocket 10 is provided between this end 8 and the opening 4 so that moisture may collect therein.

This spiral passage groove provided on the device 5 permits of a cool smoke and has all the advantages of the long stemmed pipe besides being compact in structure and giving the appearance of an ordinary or common pipe with a short stem.

An extension 11 is provided on the end of the device 5 adjacent the mouth piece 6 in order that pliers or the like may be engaged therewith for pulling the device 5 from out of the bore of the stem 3 when it is desired to clean this device.

It will be seen from the foregoing that in accordance with my present invention I have provided a smoking pipe having a stem provided with an elongated passage so that the smoke drawn therethrough will have an opportunity of becoming cool so as to not burn the tongue of the user and in which the nicotine and other liquid will be settled or absorbed in a portion of the passage before it has an opportunity of reaching the mouth of the user. The pipe also is compact in structure, durable, and may be manufactured at a very low cost thereby being practical and desirable.

I have in the present instance, shown and described only the preferred embodiment of the invention which will give in practice satisfactory and reliable results, and it is to be understood that the same is susceptible of modification in various particulars with-

2
out departing from the spirit or scope of the invention as hereinafter claimed.

Having thus described my invention what I claim as new is:—

- 5 1. A smoking pipe of the class described including a bowl having a concaved bottom, a stem having a bore, a mouth piece mounted on the stem, said concaved bottom of the bowl provided with an opening in its side, leading into the bore of the stem, a tube disposed within the bore and having an end of conical formation with an opening adjacent the first mentioned opening and spaced therefrom so as to form a pocket, a rod disposed within the tube and constructed with a spiral grooved periphery leading into the mouth piece.
- 10 15 2. A smoking pipe of the class described

including a bowl, a stem integrally extending from the bowl and provided with a bore, 20 said bowl and stem provided with a restricted opening between the interior of the bowl and the bore of the stem, a mouthpiece attached to the stem, a tube within the bore of the stem having a restricted opening a 25 spaced distance from the first restricted opening so as to form a pocket, and an elongated passage forming device within the tube.

In testimony whereof I affix my signature 30 in presence of two witnesses.

CHARLES W. NEISWENDER.
